UNITED STATES PATENT OFFICE.

JOHN STEMBER, OF NEW YORK, N. Y.

DESIGN FOR A BODY FOR BELTS.

SPECIFICATION forming part of Design No. 33,441, dated October 23, 1900.

Application filed September 28, 1900. Serial No. 31,456. Term of patent 34 years.

To all whom it may concern:

Be it known that I, JOHN STEMBER, a citizen of the United States, residing at New York, borough of Manhattan, and State of New York, have invented and produced a new and original Design for Bodies for Belts, of which the following is a specification, reference being had to the accompanying drawing, forming part thereof.

10 As shown in the drawing, the leading or material feature of my design consists of a bar A, around which are twisted the snake-shaped bodies B. The anterior portions of the bodies B are formed in a knot C, and the

posterior portions emerge from the ends of 15 the bar A. Shoots D radiate from the bar A, so as to impart the impression of a partially-trimmed branch of a tree.

What I claim is—

The design for a body for belts, substantially as shown and described.

In testimony that I claim the foregoing as my invention I have signed my name in presence of two subscribing witnesses.

JOHN STEMBER.

Witnesses:

PAUL GOEPEL,

GEO. L. WHEELOCK.
